UNITED STATES PATENT OFFICE

JOHN A. BROOKS, OF DETROIT, MICHIGAN

CUSHION HEAD FOR SPRAYING DEVICES

Application filed April 11, 1927. Serial No. 182,694.

This invention relates to spray heads of the type used for sprinkling lawns or other places requiring the spray heads to be normally beneath the surface of the ground and 5 automatically movable to spraying position when the fluid is supplied thereto.

Devices of this character are ordinarily of metal, and the upper portion is usually positioned slightly below or substantially flush 10 with the surface of the ground so as not to be noticeable or constitute an obstruction. While these devices are useful in most places, they are not adapted for athletic fields, golf 15 courses or similar places. For example, in the case of golf, a hard surface is provided upon which a golf ball will bounce and therefore detract from normal playing of the game. Furthermore, on the putting green it has not heretofore been practical to employ automatic 20 sprinklers of this type, because the ball rolling over a smooth hard surface does not move in the same manner as over a grass surface, as will be obvious. The problem is not alone present with the game of golf, but other 25 sports, as baseball, find similar objections to the use of these devices.

The usefulness of an automatic sprinkling device of this character in connection with athletic fields of various descriptions will at 30 once be appreciated, and it is a desideratum that a practical spraying device be produced which will not detract from or interfere with the proper playing of an out-of-door game and is efficient for spraying purposes.

An object of this invention is to provide 35 such device which may be used on athletic fields without interfering with the usual and proper playing of the games. Other objects will hereinafter appear.

In accordance with the invention, I provide 40 a non-metallic annulus, preferably of rubber, which covers the top of the spray head, and is suitably secured thereto. The annulus is of yielding nature and simulates in 45 action a grass surface in that it yields to pressure, but is sufficiently rigid to be supporting and suitably resistant to withstand the impact of an object against it. It has been found 50 that this annulus has satisfactorily overcome

the above problems and is admirably adapted for the purpose intended.

By way of illustration the invention is shown on the accompanying drawings, in which:

Fig. 1 is a side elevation of a spray head with a portion thereof in section; Fig. 2 is a top plan view of the spray head shown in Fig. 1; and Fig. 3 an elevation of another form of spray head with some parts in section.

The illustrated embodiment of the invention shown in Figs. 1 and 2 comprises a casing 1 having at its upper end an outwardly extending flange portion 2. The general construction and operation of this spray head is shown and described in the patent to John A. Brooks, Lawn sprinkling means, Number 1,192,743, issued July 25th, 1916, and it is not deemed necessary to describe the construction and operation of this spray head in detail. It will be sufficient to say that this spray head is of the type having a nozzle movable longitudinally within the casing 1 and having a cap on closure member 3, which in normal 65 position seats on a ledge 4 formed on the flange portion 2, but when pressure fluid is supplied to the inner end of the nozzle, the nozzle and closure are forced outwardly and the closure swings to one side to permit water 70 from the nozzle to be sprayed in the desired manner. The general construction and operation of this spray head is described in the above patent and is well known to those 75 skilled in this art.

Formed on the outer edge of the flange portion 2 is an upstanding rim 5, and the ledge 4 is shorter than outer ledge 5. The rims on ledges 4 and 5 form an annular groove, the opposite sides of which are flared 80 outwardly, as indicated at 6 and 7.

Covering the top of the flange portion 2 and fitting into the groove therein is a rubber ring or annulus 8 having outwardly flaring lower side edges 9 which interlock or dove tail in the flaring sides 6 and 7 of the annular groove, and has its outer edge flush with that of the rim 5. For securely wedging the lower portion 9 of the ring 8 into interlocking engagement with the rim 5, a metal ring 10 is vul- 85

canized in the lower portion of the ring 8, between the opposite sides and forces the outward flaring parts of the ring into their respective sides so as effectively to hold the ring in engagement with the flange portion 2. It is manifest that the ring 10 provides stiffness to the lower portion of the rubber ring and assists in holding the same from being lifted upwardly away from the inclined wall 5.

10 A disc 11 is attached to the cap 3 in any suitable manner, as by a screw 12 and cemented so that a secure connection is provided. Formed on the upper surface of the rubber ring 8 and disc 11 are a series of radially spaced annular ribs 13.

15 The spray head is placed in the ground with the rim 5 slightly below the surface of the ground and the rubber annulus 8 and disc 11 is positioned substantially flush with the 20 surface of the ground. As heretofore pointed out the annulus 8 and disc 11 do not in any way interfere with the playing of any out-of-door game, such as golf, baseball or football and provide a surface which closely resembles 25 that of a dirt or grass field. When pressure fluid is introduced the disc 11 is forced upward and spraying may be readily accomplished.

30 In the form shown in Fig. 3 the casing 1^a has a nozzle 14 from the center of which projects a stem 15 having a disc 16 fixed to the upper end thereof. The disc 16 is provided with a rim 5^a similar in conformation to the rim 5, shown in Fig. 1. In this instance a 35 rubber disc 17 dove tails with a groove formed on the inside of the rim 5^a and is provided with a metallic ring 10^a vulcanized in the disc similar to and for the purpose hereinbefore described. The parts in this figure are shown 40 in extended position or in position for spraying, and it is to be understood that when the pressure fluid is turned off, the parts automatically drop into the casing and assume a position similar to that shown in Fig. 1.

45 The difference between the annulus shown in Fig. 1 and that of Fig. 3 resides essentially in the fact that the annulus 17 is in the form of a solid disc while in Figs. 1 and 2, two parts are provided, a ring 8 and smaller disc 50 11 which fits inside the ring 8.

It is to be understood that numerous changes in details of construction and arrangement and choice of materials may be effected without departing from the spirit of the invention, especially as defined in the appended claims.

What I claim as new and desire to secure by Letters Patent is:

1. In a lawn sprinkling system in which individual units are disposed in the ground substantially flush with the surface thereof and the spray nozzle is moved upwardly above the surface when in use, a spray unit comprising, a nozzle-receiving chamber, a 60 nozzle vertically movable in and out of said 65 nozzle, a stem projecting from said nozzle, a 70 disc on the outer end of the stem normally closing the mouth of said chamber, a vertical upward extending wall on said disc having its inner circumferential face inclined toward the axis of the disc, and a relatively thick flat rubber covering for said disc and wall extending outwardly from the upper surfaces of the disc and wall and having its lower portion anchored in said peripheral wall.

75 2. In a lawn sprinkling system in which individual units are disposed in the ground substantially flush with the surface thereof and the spray nozzle is moved upwardly above the surface when in use, a spray unit comprising, a nozzle-receiving chamber, a nozzle vertically movable in and out of said chamber, a stem projecting from said nozzle, a disc on the outer end of the stem normally closing the mouth of said chamber, a vertical upward extending wall on said disc having its inner circumferential face inclined toward the axis of the disc, and a metallic ring adjacent the base of said disc for retaining the edge portion thereof within said peripheral wall.

80 3. In a lawn sprinkling system in which individual units are disposed in the ground substantially flush with the surface thereof and the spray nozzle is moved upwardly above the surface when in use, a spray unit comprising a nozzle member, a casing member for said nozzle member, a substantially flat surface associated with one of said members, a vertical upwardly extending wall around said surface having its inner circumferential face inclined toward the axis of said surface, and a relatively thick rubber covering for said surface and wall and having its lower portion anchored in said peripheral wall.

85 4. In a lawn sprinkling system in which individual units are disposed in the ground substantially flush with the surface thereof and the spray nozzle is moved upwardly above the surface when in use, a spray unit comprising a nozzle member, a casing member for said nozzle member, a substantially flat surface associated with one of said members, a vertical upwardly extending wall around said surface having its inner circumferential face inclined toward the axis of said surface, and a relatively thick rubber covering for said surface and wall and having its lower portion anchored in said peripheral wall.

90 In testimony whereof I have hereunto signed my name to this specification.

JOHN A. BROOKS.
